UNITED STATES PATENT OFFICE.

MYRON L. HAFER AND JULES H. ROSENBERG, OF PHILADELPHIA, PENNSYLVANIA.

LOCKING DEVICE FOR SAVINGS DEPOSIT BOXES.

Application filed June 30, 1922. Serial No. 571,911.

To all whom it may concern:

Be it known that we, MYRON LYMAN HAVER and JULES HARRY ROSENBERG, both citizens of the United States, and both residing in the city and county of Philadelphia, State of Pennsylvania, have invented a new and useful Locking Device for Savings Deposit Boxes, of which the following is a specification.

10 Our invention consists of a novel construction of a locking device for a savings deposit box which can be cheaply constructed, is not liable to get out of order and is provided with a bottom closure of a novel 15 construction which is readily locked and unlocked by a simple appliance adapted to be threaded into the lower portion of the locking device whereby locking tongues are bowed or deflected so as to enable ready access to be had to the interior of the locking 20 device.

It further consists of other novel features of construction and advantage, all as will hereinafter more fully appear in the detailed 25 description.

For the purpose of illustrating our invention, we have shown in the accompanying drawings a typical embodiment thereof which is at present preferred by us, since it 30 will give in practice satisfactory and reliable results, although it is to be understood that the various instrumentalities of which our invention consists can be variously arranged and organized and that our 35 invention is not limited to the precise arrangement and organization of these instrumentalities as herein shown and described.

Figure 1 represents a vertical sectional view of a locking device, embodying our invention, showing the normal position of the parts when the locking device is in closed or locked position.

Figure 2 represents a section similar to Figure 1, showing the position and manner of applying the unlocking member and the general relative position of the parts when it is desired to unlock the locking device or to have access to the interior thereof.

Figure 3 represents a series of perspective views showing the various elements comprising the locking device in detached position and the manner of assembling the same.

Figure 4 represents a side elevation of the locking rod or stem employed, in detached position.

Similar numerals of reference indicate corresponding parts.

Referring to the drawings,

In the construction of our locking device, we employ an outer casing or body 1 which is preferably composed of the cylindrical or other wall 2 having the closed top 3 provided with the slot 4 for the insertion of the coins, said top having the central hole 5 through which the locking rod or stem 6 is inserted, said stem having the cylindrical body 7, above which is the milled or knurled head 8, said stem terminating in the threaded terminal 9, whose function will be hereafter referred to.

The bottom end of the casing 2 is open and when the parts are assembled is closed by the disc 10 having the central hole 11 therein. The studs 12 are provided with heads and are secured in the top of the disc 10 and pass through the holes 13 of the transverse bar 14 which has the central hole 15 through its central straight portion 16.

17 designates a plug having the shoulder 18 and the upward extension 19 which is externally threaded and when assembled passes through the hole 15 of the bar 14 and the hole 20 of the disc 21, which has the radial cuts 22 therein forming the resilient tongues 23, whose ends project slightly beyond the periphery 24 of the disc 21. 25 designates a nut adapted to engage the threaded extension 19, which has the threaded hole 26 therethrough.

The manner of assembling the various elements comprising the closure for the bottom of the bank will be readily understood from Figure 3, the parts when in assembled position appearing as indicated in Figure 1, wherein the tongues 23 are shown as engaging the annular internal projecting flange 27. The coins are dropped into the slot 4, as is customary, and when the bank is full or it is desired to obtain access to the interior thereof, it is only necessary for the threaded end 9 of the stem or rod 6 to be inserted through the hole 11 in the bottom disc 10 and screwed into the internally threaded bore 26 of the plug 17, as indicated in Figure 2.

As the shoulder 28 of the body 7 contacts with the bottom of the relatively stiff disc 10 and the threaded stem 9 is screwed into engagement with the threaded hole 26 of the plug 17, it will be apparent that the central portion of the disc 21 will be drawn downwardly towards the disc 10 and be

slightly bowed as seen in Figure 2 and the tongues 23 will also assume the bowed or flexed position seen in Figure 2, so that the ends of the tongues 23 are disengaged from the flange 27, whereupon the bottom closure of the bank comprising the discs 21 and 10 and their adjuncts can be readily removed or withdrawn downwardly and outwardly as a unit.

10 When it is desired to insert the bottom closure in place it will be apparent that the same can be readily inserted and when the threaded stem 9 is screwed out of engagement with the plug 17, the parts will appear as seen in Figure 1 and the bottom of the bank will be closed so that no access can be had to the interior thereof.

The bottom disc 10 fits nicely into the counter-bore 29, and the heads 30 of the studs 12 hold the disc 10 in position with respect to the bar 14, while the plug 17 and nut 26 hold the bar 14 and the disc 21 in assembled position as a unit.

It will be understood that when it is desired to lock the bottom of the bank, the disks 21 and 10 and their adjuncts are inserted in the bottom and the locking device 6 is then inserted through the top 3, as seen in Figure 1, so that when the threaded stem 9 is turned into engagement with the threaded hole 26, the ends of the resilient tongues 23 will be flexed so that the parts will spring into the position seen in Figure 1. The locking device 6 is then removed and the bank or savings deposit box then appears as seen at the upper portion of Figure 3.

It will be understood that the transverse bar 14 and the disk 24 can be held in assembled position by other means equivalent to that shown, since it will be apparent that the nut 25 may be dispensed with and the upper end of the threaded extension 19 riveted upon the disk 21, if desired.

45 It will now be apparent that we have devised a novel and useful locking device for a savings deposit box, which embodies the features of advantage enumerated as desirable in the statement of the invention and the above description, and while we have, in the present instance, shown and described preferred embodiments thereof which will give in practice satisfactory and reliable results, it will be understood that the same is 55 susceptible of modification in various particulars without departing from the spirit or scope of the invention or sacrificing any of its advantages.

Having thus described our invention, what we claim as new and desire to secure by Letters Patent, is:—

1. A savings deposit box comprising a casing closed at its top and open at its bot-

tom, an inner projection on the lower portion of said casing, a flexible disk having resilient 65 tongues engaging said projection, and means operated from the bottom of said casing for flexing said tongues, said disk closing the lower portion of said casing.

2. A savings deposit box comprising a 70 casing closed at its top and open at its bottom, an inner projection on the lower portion of said casing, a flexible inner disk having resilient tongues engaging said projection, an outer relatively stiff disk forming a closure for the bottom of said casing and having a hole therethrough, a threaded member carried by said flexible disk and an outer rotary threaded unlocking device 75 adapted to engage said threaded member and flex said tongues so as to enable the latter to be disengaged from said projection.

3. A closure for a bank, comprising a bottom disk, a transverse bar having holes in its ends, studs common to said bar and disk, a flexible disk having radiating slots therein forming radial tongues, means for securing said bar and flexible disk in assembled position, an internally threaded plug, and a threaded stem adapted to engage the threaded bore of said plug and provided with a shoulder adapted to engage the bottom of said outer disk, so as to flex said tongues when said stem is rotated.

4. A savings deposit box comprising a 90 casing closed at its top and open at its bottom, an inner projection on the lower portion of said casing, a flexible disk having resilient tongues engaging said projection, means operated from the bottom of the casing for flexing said tongues, an outer disk closing said casing, a transverse bar below said flexible disk and having holes in its ends, studs common to said holes and said outer disk, a plug for holding said bar and flexible disk in assembled position, and a threaded stem engaging the internally threaded bore of said plug and provided with a shoulder bearing on the bottom of said outer disk, so that upon the rotation of said stem said tongues will become flexed and disengaged from said projection.

5. A savings deposit box comprising a 100 casing, closed at its top and open at its bottom, an inner projection on the lower portion of said casing, a flexible disk having resilient tongues engaging said projection, an outer disk and connections common to said disks for enabling them to be removed as a unit.

MYRON L. HAVER,
JULES H. ROSENBERG.
